DEPTH CHARGE FIRING CONTROL MECHANISM

Solomon Burg, Kensington Heights, Md., and Thomas C. Smith, Poughkeepsie, N. Y.; said Smith assignor, by mesne assignments, to the United States of America as represented by the Secretary of the Navy

Application March 18, 1953, Serial No. 343,208

4 Claims. (Cl. 102—16)

The invention described herein may be manufactured and used by or for the Government of the United States of America for governmental purposes without the payment of any royalties thereon or therefor.

This invention relates to improvements in naval ordnance, and its underlying purpose is to improve the depth-set valve mechanism of underwater explosive charges.

The improvement has special reference to United States Patent 2,438,117 of March 23, 1948, Walter B. Ellwood for Valve for Depth Charge Firing Mechanisms, which in practice was found to develop several faults. By reference to the patent it is noted that a ball valve is seated in the conical concavity of a ball-centering flange. This was found to have a tendency to leak water because of its being loose in the cavity could not be prevented from damaging one side of the seat during testing.

Further, a large coil spring immediately behind the ball-centering flange was found responsible for some erratic opening pressures because of failure to maintain a uniform seating on a conical rest provided for it. Because of the inherent resilience of the spring, the end loop would open slightly, allowing the spring to slip down the cone and sometimes cock off to one side. Still further, some lost motion was found to develop in the thread course of the spring seat member, functionally the depth adjusting screw, introducing some variations when adjusting that screw that were reflected in differences of force of the spring against the ball-centering flange.

Another fault of the Ellwood mechanism was an objectionable chattering of the valve assembly upon water inflow, due to the restriction.

Therefore, it is one of the objects of the invention to provide an underwater missile with means therein to increase the accuracy of the depth setting by (a) eliminating variations in the setting resulting from backlash in the threads of the adjusting screw and (b) arranging the dial and detent mechanism in such a manner as to utilize the maximum diameter of the weapon as an index to the depth setting.

Another object of the invention is to improve the nose piece of the weapon by (a) affixing the ball valve to the adjacent ball-centering flange or piston, thus to avoid damaging the valve seat during testing as by the rolling of the ball valve if it were loose, (b) providing an adequate seating for the large coil spring so that its opening pressures can be relied on and (c) supplementing the spring seat member with a leaf spring to prevent rotation of the spring seat member relative to the valve body during the making of a setting by means of the adjusting cylinder.

Another object of the invention is to increase the length of the passage around the foregoing circular flange thereby, rather paradoxically, increasing the

2

facility for water inflow into the chambers of the mechanism and thereby insuring an immediate and full opening of the ball valve member, thus to avoid any possibility of initiating a chatter.

5 Other objects and many of the attendant advantages of this invention will be readily appreciated as the same becomes better understood by reference to the following detailed description when considered in connection with the accompanying drawings wherein:

10 Fig. 1 is a central, longitudinal section of the valve assembly in detail mounted in a portion of the body section, shown in phantom, of the improved depth charge;

Fig. 2 is a sectional view taken on the line 2—2 of Fig. 1.

In the drawings the depth charge is commonly designated 11. Its intended use is in practice anti-submarine warfare. This, however, is no limitation upon the use of the missile since the identical structure and principle of operation will obtain when produced for actual warfare. It may be hand-launched or started on its air trajectory by a mechanical or explosive project of a chosen type. In the first instance the missile is simply dropped overboard or dropped from an aircraft.

25 The missile may take shapes other than that shown such as, for example, in the form of a "potato-masher" and grenade.

In Fig. 1 the depth charge 11 is shown to comprise a spherical nose piece 29, and a body section 31 which 30 may house an arming mechanism. The nose piece is built up on an annular base 33. This base is affixed by means of a mutual thread course 36 to the socket 34 of a bulkhead 35 at the forward end of the section 31. Most of the socket is filled by the base 33 and attachments, but some space is left to define the chamber 37.

35 The base 33 is provided with a central bore 38 in which a hollow cylinder 39 is turnably mounted. Turning of said cylinder occurs at depth setting. A water-tight joint is formed by sealing ring 40 and its 40 compression nut 41. The head 42 at the front end of the cylinder 39 has a central passage 43, the inner circular edge of which provides the seat for the ball valve 44. Seawater is admitted to the inside of the cylinder 39 according to the amount of unseating of 45 the ball valve.

A second ring 47, part of a sphere, completes the symmetrical shape of the nose piece. It is seated on the cylinder 39 and locked thereto by a screw 48 so that the two turn as one. A snap catch 49 operatively 50 carried by the ring 47 engages any one of several recesses 50 in the front face of the base 33 as turning occurs. The exposed perimeter of the base 33 is marked in practice with depth setting indicia from 50 to 1000 feet (not shown). These indicia are distributed to match 55 the positions of the recesses, and by locating the recesses as near as possible to the perimeter of the base it becomes possible to obtain a depth setting more easily and accurately than with the cramped arrangement in the Ellwood patent. It is the greater peripheral spacing 60 of the recesses that makes the distinction from the Ellwood structure. Any setting is held by the snapping of the detent 49 into the matching recesses.

Bolts 51 secure an inwardly flanged ring 52 against the back of the base 33. This ring has a working fit against the flanged terminal 53 of the turnable cylinder 39, rotatably mounting the cylinder on the base 33 and preventing longitudinal movement of it. The outer ends of a wide leaf spring 54 are clamped under the heads of the bolts 51. This spring is thus affixed to the base 33 and re-

mains rotationally but not axially immovable with it. The spring 54 is anchored at its middle to the inner end of an adjustable screw plug or spring seat member 55 by means of a hollow machine screw 56, thereby holding the spring seat member rotationally immovable with the base 33. Corrugations are provided in the leaf spring to permit the same to elongate axially as plug 55 is moved toward the ball and to cause the spring to exert tension on the screw plug 55 in the same direction as the force due to a coil spring 57 abutting a flat seat 58 adjacent to the opposite end of the plug.

The leaf spring 54 serves to maintain the contact of the threads in the thread course 59 between the plug 55 and the bore 60 of the cylinder 39 on the same faces at all times. The coil spring 57 is virtually dormant as far as exerting pressure against the mating faces of the threads of the thread course between 39 and 55 and seat 58 is concerned when the valve is set in its shallowest depth (50 ft.) position. The front end of the coil spring has a flat seat against the back of a freely slideable piston 61, the length of which piston is approximately equal to one-half its diameter. The side wall is circularly grooved, and its front face has a recess at 62 in which the ball valve 44 is affixed by a volume of a suitable adherent 63, usually solder. The ball is thus held in its correct position and its correct seating on the inner circular edge of the passage 43 is assured.

A rod with portions having diameters 64 and 64a and 64b extends back from the rear of the piston 61. The portion having the diameter 64 serves as a stop by abutting against plug 55 to prevent spring 57 from being compressed to a solid height. The second portion having the diameter 64a has slideable mounting in the bore 65 of the plug 55, the back end of which bore has a thread course into which the machine screw 56 is driven. The third portion having the diameter 64b is slideably mounted in the hollow of the machine screw. The nut 66 screwed on the exposed rear end of the reduction 64b, which is conveniently called a stem, is adjustable against the head of the screw 56 to determine the maximum length to which the spring 57 may extend. When the valve is set on the 50-foot setting the spring 57 does not exert any force on the mating faces of the thread course between 59 and 39 because the ball valve 44 is restrained from contacting the seat 43 by the nut 66.

Thus, the ball valve may be held open on one or more of the shallowest depth settings and hence, spring 57 need not be used to determine the depth of firing at the spring 57's nearly extended condition where it less accurately follows Hooke's Law. Therefore, on the shallowest setting, the depth of firing may be determined only by the characteristics of means such as a firing pin mechanism.

The spring 57 has predetermined compression characteristics with which the depth setting indicia on the perimeter of the base 33 are directly related. This spring is varied in its pressure against the piston 61 and in consequence in the pressure which it exerts to seat the ball valve 44, by rotation of the ring 47. In other words, if the depth setting is to be for the 300-foot mark, the turning of the ring 47 will rotate cylinder 39 and result in plug 55 being moved axially an amount such that the spring exerts a force on the ball valve equal to the force exerted by the external hydrostatic pressure of water at a depth 300 feet below the surface.

Slight unseating of the ball valve admits water to the face of piston 61 and immediately sets up a pressure over the entire area of the piston, displacing it backward and thus fully opening the valve. Merely admitting water does not accomplish any purpose if the flow past the piston is not properly restricted to create the foregoing pressure on the face of the piston.

To the foregoing end it is noted that there is but a moderate clearance and a fairly long skirt between the perimeter of the piston and the wall of the cylinder 60. The first purpose is to get maximum opening to and

quickest possible filling of chamber 37. The second purpose is to make the valve so that it will not close by back-pressure before actuation of a firing release mechanism, for example. In other words, the build-up of pressure in chamber 37 must operate means such as a firing pin at the established setting before the back-pressure reaches the level at which it would counter-move the piston and again close valve 44. If the latter happened during the sinking of the depth charge, the latter would have to go down much farther than intended to arrive at a pressure level at which the valve would open again.

Unseating of the valve 44 admits water to the chamber 37 through holes 67 in the screw plug 55. This chamber adjoins the bulkhead 35 fronting a firing pin release mechanism, not shown.

Obviously modifications and variations of the present invention are possible in the light of the above teachings. It is therefore to be understood that within the scope of the appended claims the invention may be practiced otherwise than as specifically described.

What is claimed is:

1. An item of ordnance, the subcombination thereof comprising a ball valve and a hollow cylinder having a central passage defining a seat for the ball valve, a piston freely slideable in the hollow cylinder and having a recess for the ball valve, means adhering the ball valve in the recess, preventing its rolling sidewise in the recess and avoiding resulting damage to the seat on a sliding of the piston during a test operation, a ported plug disposed within said cylinder and movable thereby, means on said cylinder in engagement with complementary means on said plug for moving said plug as the cylinder is rotated, means in clamping engagement with said plug for causing the plug to move axially in response to rotation of the cylinder, means carried by said cylinder for imparting rotary movement thereto, spring means in engagement with said plug and piston and controlled by said plug for maintaining the ball valve in engagement with said seat, and means including a flange on said cylinder for preventing axial movement of the cylinder as the cylinder is rotated.

2. An item of ordnance, the subcombination thereof comprising a ball valve and a hollow cylinder having a central passage at one end defining a seat for the ball valve and having a thread course at the other end, a base for rotatably supporting said cylinder, flange means on said cylinder in engagement with complementary means on said base by which the cylinder is swivelled on the base to turn but not move axially, a ported plug screwed into the thread course and movable axially therein as the cylinder is rotated, a movable piston in the hollow cylinder, a stem on said piston disposed within said plug and slideably guided by the plug, a coil spring abutting the piston and plug and controlled by said plug as the plug is moved axially for maintaining the ball valve seated, means carried by said cylinder for rotating the cylinder and axially shifting the plug at the thread course thereby to adjust the compression of the coil spring, said last-named means being selectively settable to different settings relative to said base, means carried by said base in sealing engagement with the cylinder for providing a watertight connection therebetween, and a leaf spring affixed to the screw plug and to the base to prevent turning of the plug without lost motion.

3. The structure of claim 2 wherein the leaf spring is corrugated crosswise of its length to exert a tension on the plug to maintain the contact of the threads on abutting faces.

4. An item of ordnance, the subcombination thereof comprising a ball valve, a hollow cylinder having a central passage at one end defining a seat for the ball valve and having a thread course at the other end, a base for rotatably supporting said cylinder, flange means on said cylinder in engagement with complementary means on said base by which the cylinder is swivelled on said base for rotary movement and by which the cylinder is held

against axial movement, a ported plug screwed into the thread course and having a bore, said plug being movable axially as said cylinder is rotated, means carried by said cylinder for rotating said cylinder, said last-named means being selectively settable to different settings relative to 5 said base, a piston in the cylinder having a recess containing the ball valve and having a rod slidable in the bore, a coil spring abutting the piston and plug and controlled by said plug for urging the ball valve into engagement with its seat, a stem integral with the rod and extending out of the bore, and a nut screwed onto the extension of the stem to exert pressure against the plug thus to preset the coil spring and hold the valve open so that it is inseparable at the shallowest setting. 10
